ABSTRACT: A large transverse parallel plate finned heat exchanger section is constructed with a plurality of transverse horizontal spaced rows of vertically aligned fluid-conducting tubes of flat cross section, soldered to the parallel plates to form a bracing bar construction which will permit the exchanger to be readily cut into a number of small units along a vertical plane extending through the center of the flat tubes in a given row. Flat tubular support pieces disposed in spaced vertical rows extending through the parallel plates can also be used independently of the fluid-conducting tubes extending therethrough to permit cutting of sections in a vertical plane along these pieces without disturbing the fluid-carrying tubes.

HEAT EXCHANGER UNIT

DESCRIPTION OF INVENTION

This invention relates to finned heat exchanger units.

It is a principal object of this invention to provide for a finned heat exchanger unit which can readily be divided into a number of smaller sized heat exchanger units.

It is a still further to provide a simple large heat exchanger block which can readily be divided into a number of smaller heat exchanger units without damage to the units.

It is a still further object of this invention to provide a special reinforcing construction to a finned parallel plate heat exchanger unit which will permit the heat exchanger unit to be cut without damaging the fin structure of the units.

In the past, it has been customary to mount such heat exchanger units singly in the size desired. This approach requires considerable time and is costly. It has been suggested previously to initially mount the heat exchanger unit to multiple unit width and then cut such unit to smaller sizes to obtain a plurality of units. This technique has not worked satisfactorily in the past because of the thinness of the plates or fins, which in some instances may be only .1 millimeter in thickness so that they are usually bent out of line even when a low cutting speed is used.

To avoid this difficulty in the past elongated holes were made in the plates along a possible line of severance to reduce the cutting required, and thus simplify the severance problems encountered. However this approach did not overcome the risk of bending the edges of the parallel plates, nor overcome the frictional problems associated with cutting.

The present invention seeks to improve the heat exchanger construction in such a way that small units can be severed from a larger heat exchanger block efficiently and economically without damage to the units severed.

Consequently, substantial costs savings are realized by avoiding the need for special sized units, and by providing a simple method of severing smaller sized heat exchanger units from a large block without damage to the separated pieces.

DESCRIPTION OF THE DRAWINGS

FIG. 1 shows a perspective view of the heat exchanger unit of the subject invention.

FIG. 2 is a section along lines 2-2 of FIG. 1 and viewed in the direction of the arrows.

FIG. 3 is a view similar to FIG. 2 showing an alternate embodiment of this invention.

DESCRIPTION

Referring to FIG. 1, a heat exchanger block unit is shown comprising on one hand a plurality of thin-walled tubes of flat cross section which are arranged in rows and parallel to each other for the passage of the heat carrier, and on the other hand a plurality of parallel plates or fins soldered to said tubes and acting as air baffles; smaller units are formed by severing the heat exchanger block into a smaller unit width.

Heat exchanger units of the type indicated are used mainly in the construction of vehicles or for stationary use as coolers. The use of such units as room-heating radiators, however, also is feasible.

The embodiment of FIG. 1 shows horizontally extending flat tubes 1 of a heat exchanger unit form vertical and horizontal rows and are made of tinned brass, and the outside cross section has a width of 2 millimeters and a height of 12 millimeters. The wall thickness is .25 millimeters, and the horizontal distance from tube center to tube center is 10 millimeters. The tubes 1 are fixed with respect to each other by the fins 2 mounted thereon and serving as air-conducting baffles. The fins 2 are of .1 millimeter thickness, are closely spaced and are made of leaded sheet iron. In the planes of the vertical longitudinal sidefaces 3 and 4 of the unit are arranged tube half portions 1a of a vertical row of tubes (only the face 3 is visible). The tube halves 1a are made by joining tubes 1 and baffles 2 to form a block (not shown) of multiple unit width, then are sol-

dered to each other and subsequently cut up into units of the desired size. The saw cuts are passed through the middle of vertical tube rows. Due to the flat tube cross section and a correspondingly measured width of cut, there result the flat end 5 or terminal strips 1a which thus are countersunk in recesses provided in the fin edges. These strips 1a stabilize or brace the longitudinal side faces 3, 4 or respectively the edges of the baffles 2 which form said faces. Such stabilizing or bracing is effective during the process of separation and later on against mechanical stresses. The end faces of the unit are formed by end plates 5 of which only one is visible in the drawing.

In accordance with the present invention, the longitudinal sides of the heat exchanger unit can also be stabilized by 10 means of flat bars extending parallel to the tubes, countersunk in recesses of the cross leaf edges and soldered to the cross leaves as shown in FIG. 3.

According to a further aspect of the invention, in the method of producing the present heat exchanger unit, when 15 mounting a heat exchanger block comprising tubes and cross leaves and being of multiple unit width, stabilizing bars are disposed in the separation planes, and after soldering the block the separation sections or cuts are passed through said bars in such a way that one half of each bar will be a component of one unit and the other half will be a component of the other unit.

By passing the sections or cuts through stabilizing bars, the 20 cross leaves or respectively the cutting edges thereof cannot bend during the severing operation which can proceed at high speed. A further advantage is that the longitudinal sidefaces produced by severing a block into several units, are stabilized at once by the halves of said bars, *i.e.* the mutual distances of the separating edges of the cross leaves are defined on the half portions of the stabilizing bars and protected from being bent 25 due to mechanical influences, which is highly important for stocking, for transport and even in the mounted condition of the elements.

To raise the cutting speed and for reasons of saving material 30 it is recommended to use flat hollow bars for stabilizing, so that for each bar only double the wall thickness has to be cut through. Further advantages are obtainable by passing the cuts for subdividing a block having multiple unit width through any vertical rows of tubes for the passage of the heat carrier. In the last-mentioned type of fabrication it is not 35 necessary to insert special stabilizing bars into the block. The only requirement is that the superjacent tubes are in vertical flights. In this manner one is entirely free in the choice of the unit width which may be any multiple of the horizontal distance of two adjacent vertical rows of tubes.

The invention is very significant for the use of heat 40 exchanger unit as room-heating radiator. Although units of different widths are required for different building projects, any desired number of units may be prefabricated and stocked in the form of blocks. After receiving an order, merely a corresponding number of these blocks have to be cut up to units 45 of the desired widths so as to deliver any order without loss of time. Otherwise customary or conventional additional charges for executing small orders will be reduced to a minimum. For the reasons mentioned before, the invention has made possible 50 for the first time to open the heating field or branch in an economical way and manner to a heat exchanger unit built up in the manner of an automobile radiator.

While the invention has been described, it will be understood 55 that it is capable of further modifications and this application is intended to cover any variations, uses, or adaptations of the invention following in general, the principles of the invention and including such departures from the present disclosure as come within known or customary practice in the 60 art to which the invention pertains, and as may be applied to the essential features hereinbefore set forth and as fall within the scope of the invention or the limits of the appended claims.

I claim:

75 1. A heat exchanger unit comprising:

- a. a plurality of heat exchanger fins of parallel thin gage sheets of heat-conducting material forming a block having top, bottom, front, rear and sidewalls;
  - b. a plurality of vertically spaced recesses formed in said sidewalls;
  - c. a plurality of laterally spaced vertical rows of vertically spaced conducting tubes extending transversely through said heat exchanger fin and rigidly secured to said heat exchanger fins;
  - d. a plurality of vertically spaced horizontally extending individual bracing elements in said recesses and rigidly secured to said heat exchanger fins; and
  - e. each of said bracing elements comprising approximately one-half of a longitudinal vertical section of said conducting tubes.
2. A heat exchanger unit as in claim 1 and wherein said conducting tubes are substantially flat in cross section.
3. A heat exchanger unit as in claim 2 and wherein:
- a. the flat side of said conducting tubes are vertical; and

- b. said vertical rows of conducting tubes are substantially equally spaced.
- 4. A heat exchanger unit comprising:
  - a. a plurality of heat exchanger fins of parallel thin gage sheets of heat-conducting material forming a block having top, bottom, front, rear, and sidewalls;
  - b. a plurality of vertically spaced recesses formed in said sidewalls;
  - c. a plurality of laterally spaced, vertical rows of vertically spaced conducting tubes extending transversely through said heat exchanger fins and rigidly secured to said heat exchanger fins; and
  - d. a plurality of vertically spaced, horizontally extending individual bracing elements in said recesses and rigidly secured to said heat exchanger fins, and each of said bracing elements comprising approximately one-half of a longitudinal vertical section of a solid bar.
